(57) **CLAIM**

The ornamental design for a mount for multiple cameras capturing 3D content, as shown and described.

DESCRIPTION

FIG. 1 shows a front perspective view of a mount for multiple cameras capturing 3D content according to my invention.

FIG. 2 shows a top plan view thereof.

FIG. 3 shows a bottom plan view thereof.

FIG. 4 shows a right side elevational view thereof; and,
FIG. 5 shows a front elevational view thereof.
